DESIGN FOR A LAMP SHADE

Eugene Schwarz, Alexandria, Ind., assignor to
The Mantle Lamp Company of America, Chi-
cago, Ill., a corporation of Illinois

Application August 6, 1934, Serial No. 52,834

Term of patent 3½ years

To all whom it may concern:

Be it known, that I, EUGENE SCHWARZ, a citizen of the United States of America, residing at Alexandria, in the county of Madison and State of Indiana, have invented a new, original, and ornamental Design for Lamp Shades, of which the following is a specification, reference being had to the accompanying drawing, forming a part thereof:

Fig. 1 is a diagrammatic view of a frusto-coni-

cal lamp shade, showing the outlines of my lamp shade when assembled, and

Fig. 2 is a plan of the lamp shade, which has been opened up or developed, showing my new design.

I claim:

The ornamental design for a lamp shade, substantially as shown and described.

In testimony whereof I affix my signature.

EUGENE SCHWARZ.
